UNITED STATES PATENT OFFICE

HERMANN HEMSCHEIDT, OF WUPPERTAL-ELBERFELD, GERMANY

LOADING MACHINE FOR HEAPED MATERIAL OF EVERY DESCRIPTION

Application filed March 12, 1932, Serial No. 598,469, and in Germany May 1, 1931.

The invention relates to a loading machine for dumped material of every description, and it is intended for receiving, transporting, particularly in an upward direction and, 5 should the necessity arise, for throwing off the material being handled, the latter operation coming into consideration chiefly for stowage in mines, that is to say, for filling up the excavations remaining after the minerals have been removed. In particular the invention provides for the use of a loading member consisting of a shaft carrying fingers, teeth or the like, this shaft working in connection with a kind of fixed comb or 10 grid in such a manner that the fingers pass through the spaces between the teeth of the comb or grid with a certain amount of clearance. The dumped material, which is scooped up by the fingers revolving at a correspondingly high speed and carried along 15 by them, is prevented by this comb, acting as a stripper, from being carried farther in the direction of rotation of the shaft. Instead, the material is either delivered on to 20 a conveyor connected therewith, or it is thrown off when the loading member is used as an ejecting device.

This member is designed to comply with the special purpose it may be intended for, 30 and its construction is described with the aid of an example shown in the drawings in which the element is first shown arranged for use as a loading device, while in the second instance a corresponding element is indicated 35 designed as a discharging device on the same machine.

Fig. 1 is an elevation of the device.

Fig. 2 is a plan.

Figs. 3 and 4 show the loading element, 40 drawn to a larger scale and detached from the complete machine, specially designed for the first-named purpose.

Figs. 5 and 6 show the loading element specially designed for the second purpose.

45 The material dumped on the floor is scooped up by the shaft *a* provided with the fingers *c* and carried along by them. An intermediate member *u*, extending the entire width, is arranged between the shafts *a* and *b*, the latter being the pivot of the conveyor *d*.

This intermediate member *u* is provided with teeth *v* similar to the teeth of a comb which reach partly over the shaft *a* so as to allow the fingers *c* to pass through the spaces between the teeth of the comb, thereby depositing the material carried along. 55 The teeth *v*, formed as tongues similar to strippers, reach so far over the shaft *a* and are so curved that the angle formed between the fingers *c* and the upper face of the teeth *v* is always greater than the friction angle 60 against the material being handled. Means are thus provided for preventing the revolving fingers from taking up the material and either crushing it like a crusher would do, or from jamming, owing to the presence of a particularly hard substance in the loading material, for instance, a piece of iron which may have found its way into the 65 heaped material. As in every position of the fingers *c* relatively to the strippers, the angle is great, the material is actually squeezed away or even hurled away over the member *u*. It will be noted that the upper 70 surfaces of the teeth *v* are substantially tangent to the shaft *a* and that the front sides of the fingers *c* of said shaft are nearly radial. 75 Hence while the fingers are effective in raising the material over the shaft, their nearly radial front sides coact with the substantially tangential upper surfaces of the teeth *v* to throw the material over the member *u*, as above stated. The rear side of the member *u* is concave and provided with an extension *x* so that it forms a loading trough *y* for the 80 returning conveyor revolving round the shaft *b*. Any material entering between the body *v* and the conveyor *d* will be picked up 85 and carried along again by the spud *e* which is shown just rising in the trough *y*.

90 In the example embodying the invention the other turning point of the conveyor, based on the corresponding loading element, is formed as a device for throwing off the material, a device of this kind being of special advantage notably for mining purposes as a means of discharging the material fed forward by the conveyor. In accordance 95 therewith, the shaft *a'* is arranged at the upper end of the inclined conveyor *d*, this shaft 100

being indirectly driven at a correspondingly high speed by the conveyor motor B and provided with the fingers c' which are arranged, by way of example, in two oppositely disposed and offset rows. These fingers c' rotate with a suitable amount of clearance between the teeth v' of the concave member u', the teeth extending about two thirds of the periphery as walls forming single chambers, the teeth being omitted on the remaining third portion. This cavity is so arranged in respect of the turning point of the conveyor d that the stowage material thus fed forward to this point falls into the cavity where it provisionally rests on the comb or grid formed by the teeth v' until it is caught by the fingers c' and thrown off, whereby fine-grained material, which may have dropped into the interstices, is effectually expelled. After the fingers c' have passed through the cavity in the toothed member u', they again enter the spaces of the comb or grid on the other side. To prevent jamming of particles of the stowage material between the fingers c' and the teeth v', and rather to ensure the material being again ejected or squeezed out, the finger is formed into a curve c'' on the front facing the direction of movement so that the angle between the face of the tooth and the finger is always greater than the friction angle.

I claim:

1. In a machine of the class described, in combination with a rotary gathering element comprising a shaft and fingers projecting from the periphery thereof and the front side of each of which is at a slight angle to a radius of said shaft and converges rearwardly to said radius, a member adjacent the rear side of said rotary gatherer and provided with spaced teeth which project therefrom close to and partly over the upper rear side of the shaft of the gatherer element and the upper sides of which teeth are substantially tangentially arranged with respect to said shaft, so that the fingers of the gatherer element and the teeth of said member coact to strip material from the gatherer element and throw the same over said member.

2. In a machine as claimed in claim 1, the combination with the rotary gatherer element and the stripping member, of an endless conveyor between the front portion of which and the rotary gathering element the stripping member is arranged and in which the stripping member has a concave rear face presented to the conveyor and also has at its lower side a portion extending somewhat under the conveyor.

3. In a machine of the class described, the combination with a rotary gathering element comprising a cylindrical member and fingers projecting substantially radially therefrom, of a conveyor spaced from the rear side of

said gathering element and a stripping member arranged between said gathering element and said conveyor, said stripping member having concave faces on opposite sides respectively presented to and conforming with the gathering element and the conveyor and also having teeth on the side presented to the gathering element, said teeth closely approaching and extending partly over the upper rear side of the cylindrical member of the rotary element and the upper sides of said teeth being substantially tangent to said cylindrical member.

In testimony whereof I affix my signature.

HERMANN HEMSCHEIDT.
